UNITED STATES PATENT OFFICE.

JAMES BAIRD, OF ARDMORE, PAPAKURA, NEW ZEALAND.

AUTOMATIC CANDLE-EXTINGUISHER.

1,308,215.

Specification of Letters Patent.

Patented July 1, 1919.

Application filed February 7, 1918. Serial No. 215,819.

To all whom it may concern:

Be it known that I, JAMES BAIRD, a subject of the King of Great Britain, residing at Ardmore, Papakura, New Zealand, have 5 invented certain new and useful Improvements in Automatic Candle-Extinguishers; and I do declare the following to be a full, clear, and exact description of the invention, such as will enable others skilled in the art 10 to which it appertains to make and use the same.

My invention relates to improvements in devices for automatically extinguishing candles when they have burned a predetermined 15 length of time, and the principal object is to provide an extremely simple and inexpensive, yet a highly efficient support for the extinguishing cap.

A further object is to provide novel means 20 for limiting the amount which the prong to be described, is permitted to penetrate the candle, whereby possible breakage of the latter is prevented.

A still further object is to provide an improved type of lever upon which the extinguishing cap is carried.

With the foregoing general objects in view, the invention resides in the novel features of construction and unique combinations 30 of parts to be hereinafter fully described and claimed, the descriptive matter being supplemented by the accompanying drawings which form a part of this specification and in which:

35 Figure 1 is a side elevation of the improved extinguisher applied to a candle;

Fig. 2 is an enlarged vertical section of the device in operative position;

40 Figs. 3 and 4 are respectively horizontal and vertical sections on the planes indicated by the lines 3-3 and 4-4 respectively of Fig. 1; and

Fig. 5 is a plan view of the sheet metal blank from which the support is constructed.

45 In the drawings above briefly described, the numeral 1 designates a support formed of a single T-shaped sheet metal blank as illustrated in Fig. 5, the shank 2 of said blank being bent substantially upon itself 50 along its longitudinal center to form a channel shaped standard 3, the two halves 4 of the head of the T extending in parallel relation from the lower ends of the side flanges 5 of said standard, to form a pair of candle gripping arms. These arms are bulged out-

wardly between their ends as indicated at 6 to provide a seat for the candle, and a suitable clip 7 is provided for holding the free ends of the arms together so as to effectively clamp the device upon the candle. 60

An angular lever 8 carries a candle extinguishing cap 9 at its upper end, said lever being formed of a single strip of metal whose two halves are angularly related and joined by an S-shaped central portion having a closed loop 10 and an open loop 11. A suitable pivot pin 12 passes through the closed loop 10 and through the side flanges 5 of the standard 3 to pivotally mount the lever 8, whereas a pin 13 extends longitudinally of the lower end of said lever with its inner end received snugly in the open loop 11, said pin being soldered or otherwise secured in place. The outer end of the pin 13 extends beyond the lower end of the lever 8 75 and is sharpened as shown at 14 to provide a prong adapted to penetrate the candle to hold the lever so as to retain the extinguishing cap 9 in inoperative position until the candle has melted sufficiently to release the 80 prong. When this occurs, however, the cap automatically drops to the position of Fig. 2 and thus extinguishes the flame.

In order to prevent forcing of the pin 13 into the candle to an extent which might 85 break the latter, it becomes highly expedient to provide a suitable stop, and although this stop could be embodied in a number of forms, I prefer to bend the lower end 15 of the lever 8 outwardly a slight distance from the pin 13 so that said end of the lever constitutes a stop for the purpose specified. Furthermore, since the lever is of greater width than the pin 13, it will serve to a 90 large extent to prevent melted wax from accumulating beneath the pin, so that the downward movement of the latter will not be obstructed when the candle has burned to the predetermined extent.

95 From the foregoing, taken in connection 100 with the accompanying drawings, it will be obvious that although my invention is of extremely simple and inexpensive nature, it will be highly efficient and durable. For these reasons, I prefer to employ the several 105 specific details shown and described, but I wish it understood that within the scope of the invention as claimed, numerous minor changes may well be made. Also, although this feature is not absolutely necessary, I 110

prefer to bend the lower edges of the arms 4 upwardly to provide reinforcing flanges 16, therefor, said flanges contacting with the outer side of said arms as shown clearly in 5 Figs. 1, 3 and 4.

I claim:

1. A candle extinguisher comprising a support formed of a T-shaped sheet metal blank bent substantially upon itself along the center of its shank to form a channel shaped standard, the two halves of the head of the T extending in parallel relation from the lower end of the side flanges of said standard and being bulged outwardly between 10 their ends to form a seat for the candle, means for drawing said halves together to grip the candle, an angular lever whose elbow is positioned between the side flanges of said standard, a pivot pin passing 15 through said flanges and said elbow, a candle extinguishing cap on the upper end of said lever, and a prong on the lower end thereof to penetrate the candle and hold said lever in position to support said cap free of 20

the candle until said prong is released by 25 melting of the candle.

2. A candle extinguisher comprising a clamp to surround the candle, a standard rising from said clamp, a lever formed of a bent strip of metal whose two halves are 30 disposed at an angle and joined by an S-shaped portion having an open loop and a closed loop, a pivot pin passing through said closed loop and pivoting said strip to said standard, a candle extinguishing cap on the 35 upper end of said lever, and a pin extending longitudinally of the other end of said lever and secured thereto, the inner end of said pin being received in said open loop and the outer end of said pin being sharpened and 40 extending beyond said strip.

In testimony whereof I have hereunto set my hand in the presence of two subscribing witnesses.

JAMES BAIRD.
